Specification for Design.

Patented May 3, 1921.

Application filed December 17, 1919. Serial No. 345,654. Term of patent 14 years.

To all whom it may concern:

Be it known that we, LEO A. DREY and JAMES L. HIATT, citizens of the United States, residing at St. Louis, Missouri, and Sapulpa, county of Creek, and State of Oklahoma, respectively, have invented a new, original, and ornamental Design for Fruit-Jars, of which the following is a specification, reference being had to the accompanying drawing, forming part thereof, in which—

Figure 1 is a side elevation embodying our invention; and

Fig. 2 is a horizontal cross section of the same through the cylindrical projections and ribs. Formed on the neck portion of the jar are cylindrical projections 7; and

on opposite sides of the cylindrical projections, semi-cylindrical projections 10 are also formed.

We claim:

The ornamental design for a fruit jar as shown and described.

In testimony whereof we have signed our names to this specification, in the presence of two subscribing witnesses.

LEO A. DREY.
JAMES L. HIATT.
